US00D676986S

(12) **United States Design Patent**
Maxik et al.

(10) **Patent No.:** US D676,986 S
(45) **Date of Patent:** ** Feb. 26, 2013

(54) **LUMINAIRE**

(75) Inventors: **Fredric S. Maxik**, Indialantic, FL (US); **David Henderson**, Indialantic, FL (US); **Mark Penley Boomgaarden**, Satellite Beach, FL (US); **Addy S. Widjaja**, Palm Bay, FL (US); **Emilio Flores**, Indian Harbor, FL (US); **Shane Sullivan**, Indialantic, FL (US); **Wei Sun**, Indialantic, FL (US)

(73) Assignee: **Lighting Science Group Corporation**, Satellite Beach, FL (US)

(**) Term: **14 Years**

(21) Appl. No.: **29/423,693**

(22) Filed: **Jun. 4, 2012**

Related U.S. Application Data

(62) Division of application No. 29/411,107, filed on Jan. 17, 2012, now Pat. No. Des. 667,971, which is a division of application No. 29/360,982, filed on May 4, 2010, now Pat. No. Des. 663,446.

(57) **CLAIM**

We claim, the ornamental design for a luminaire, as shown and described.

DESCRIPTION

FIG. 1 is a first side view of a second embodiment of the invention, the luminaire being symmetric about a center axis; FIG. 2 is a second side view of the embodiment of FIG. 1; FIG. 3 is a top view of the embodiment of FIG. 1; FIG. 4 is a bottom view of the embodiment of FIG. 1; and, FIG. 5 is a perspective view of the embodiment of FIG. 2, a reverse perspective view being the same as FIG. 6. The degree of transparency or opaqueness of the lens of the luminaire forms no part of the claimed design. The lens of the claimed luminaire may have facets, lenslets or other treatments.

The color and shading of the luminaire forms no part of the claimed design, the luminaire according to the claimed design may be any color or combination of colors.

The surface treatment of the luminaire forms no part of the claimed design, the luminaire of the claimed design may have any surface treatment.

References to “side”, “top”, and “bottom” in the figure descriptions are not meant to require certain in-use orientation; a luminaire according to the claimed design may be used in any orientation.

1 Claim, 5 Drawing Sheets
